UNITED STATES PATENT OFFICE

GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

ROTATION CONTROL MECHANISM FOR DRILLS

Application filed July 16, 1930. Serial No. 468,308.

This invention relates to fluid pressure tools and machines and more particularly to those of the percussive type equipped with rotation mechanism and used for rock drilling and similar operations. It has special application to machines of the type known as self-rotated stopers which have power means, such as fluid pressure feed legs, for advancing the percussive motor to the work and mechanism for rotating the drill steel during the drilling operation.

It is a well known fact that difficulties are experienced in hole starting with machines of the latter type because the power feed forces the drill bit against the rock and the rotation of the bit by the rotation mechanism causes the machine as a whole to crawl in a circle. Under these circumstances the machine is hard to hold and dangerous to the operator if it gets out of his grasp. Another serious situation develops when the drill steel becomes stuck and the operator cannot shut off the throttle in time to prevent the machine from getting out of control. If he releases the control handle, the machine as a whole revolves around the stationary drill steel winding up the air hose. This is likely to upset the operator and when the hose is torn loose the machine will collapse suddenly and may fall upon him.

One object of the invention is to give the operator better control over machines of the described type. Another object is to provide a conveniently operated arrangement for engaging and disengaging the rotation train so that the latter is at all times under immediate control of the operator. Another object is to cause the rotation train to disengage automatically when the machine gets out of control. Other objects will be apparent from the detailed description which follows.

In order to illustrate the invention one concrete embodiment thereof is shown in the accompanying drawings in which:

Fig. 1 is a fragmentary sectional view of the central portion of a fluid pressure stoping drill;

Fig. 2 is a transverse sectional view somewhat diagrammatic in arrangement substantially on the line 2-2 of Fig. 1; and

Fig. 3 is a fragmentary sectional view similar to Fig. 1 but showing certain of the parts in different positions.

The embodiment of the invention chosen for the purpose of illustration comprises a fluid pressure stoping drill which is conventional as to its essential parts and general arrangement. It has a fluid pressure percussive motor, which, so far as illustrated, comprises a cylinder 4 in which reciprocates a hammer piston 5 and includes rotation mechanism, a part of the rotation train comprising rifle bar 6 having a head 6a in which are mounted pawls 7 for cooperation with a ratchet ring 8, certain details of which will be more fully described hereinafter.

The percussive motor and the working tool or drill steel (not shown) supported thereby is advanced to the work by conventional feeding means such as a feed leg motor having a cylinder 9 with a piston 10 therein and a feed leg extension 10a projecting therefrom. The feed motor may be secured to the percussive motor in any suitable or desired manner as by clamping bolts 11 having heads 11a at one end and nuts 11b at the other. A control handle 12, having a grip portion 12a, extends from one side of back head 13 and admission and distribution of pressure fluid to both the percussive motor and the feed leg from inlet connection 14 (Fig. 2) is under the control of a throttle valve 15 of any suitable or desired type having an operating handle 15a.

Aside from certain features relating to the control of the rotation train, which will now be given attention, the percussive motor and the power feed and their assembly may be of any conventional or known arrangement. In order to enable the operator to "spot" or start holes with accuracy, ease, and safety, and in order to control the drilling machine in the event of a stuck steel, means for instantly breaking the rotation train are provided, which means are automatically operated when the operator releases the machine. To this end a spacing or holding member 16 is provided within back head 13 for maintaining rifle bar head 6a in engagement with closure or cylinder ring 17 in which the rifle bar has a bearing. Holding member 16 may,

if desired, serve to mount a fluid tube 18 extending axially through the percussive motor for hole cleaning purposes. Ratchet ring 8 telescopingly engages rifle bar head 6a and 5 is axially movable relative thereto. Its interior is provided with ratchet teeth 8a (Figs. 1 and 2) of sufficient length to be engaged by pawls 7 in all positions of the ring. Its exterior is provided with clutch teeth or splines 10 8b which mesh with cooperating teeth or splines 13a when ratchet ring 8 is in its rearward position (Fig. 3) and which are disengaged therefrom when the ring is in its forward position. When in the latter position 15 the forward end of ratchet ring 8 projects into an annular recess 17a in cylinder ring 17. Ratchet ring 8 has a bearing fit with back head 13 on its outside. The rear end of the ratchet ring has an annular member 8c 20 riveted or otherwise secured thereto to form a piston head which is slidable in the annular chamber surrounding holding member 16. Outside cup washers 8d are provided to form an air tight seal on the outer periphery of 25 the piston and U-washers 8e prevent air leakage at the inner periphery. The position of ratchet ring 8 is controlled by pressure fluid admitted to opposite ends of the piston chamber surrounding holding member 16 by a 30 valve 19 operated by a rod 20 extending within control handle 12 and arranged to be actuated by a lever 21 pivotally mounted at 21a in the grip portion 12a.

In the position of the parts shown in Fig. 35 1, pressure fluid entering through inlet 14 (Fig. 2) is admitted beneath piston head 8c by passage 22 (Fig. 2), valve port 23, and thence by passage 24 (Fig. 1). At the same time the opposite side of piston 8c is vented 40 to atmosphere through passage 25 and atmospheric port 26. This is the normal position of the parts inasmuch as a spring 27 yieldingly maintains valve 19 in the position shown. With the ring in its advanced position 45 splines 8b and 13a are disengaged so that ratchet ring 8 is relatively free to revolve since it now has only frictional engagement with the stationary parts of the machine, such as back head 13 and ratchet 50 ring 17. If desired, the ports controlling the admission of pressure fluid to the piston chamber for piston 8c may be so proportioned as to vary the relative pressures on the opposite sides of the piston so as to produce 55 any desired frictional engagement of ratchet ring 8 with cylinder ring 17. In the form shown it is desirable to provide atmospheric porting forwardly of piston 8c because leakage of pressure along the bearing 60 for rifle bar 6 from the rear end of cylinder 4 of the percussive motor in normal running would tend to build up pressure, particularly when the parts become worn. In the position shown the reciprocations of piston 5 of 65 the percussive motor will oscillate rifle bar

6, and pawls 7 will rotate ratchet ring 8 so that the only torque on the rotation train will be that due to friction.

When the operator desires to engage the rotation train, he slips his fingers over lever 21 and draws it to the position shown in Fig. 3, thereby forcing valve 19 to the left against spring 27. This reverses the porting arrangement so that pressure fluid now flows from live air port 23 through passage 25 to the other side of piston 8c moving the latter rearwardly. At the same time the valve opens the rearward end of the piston chamber to atmosphere through passage 24 and atmospheric port 28. With ratchet ring 8 70 in its rearward position, splines 8b and 13a will be in engagement and since the ring then cannot turn, the rotation train will cause the working tool or drill steel to rotate in the usual way. On release of control lever 21, 75 spring 27 will restore the parts to the positions shown in Fig. 1 and the rotation train will be disengaged—thus eliminating danger to the operator in the case of a stuck steel. This is also an important feature when the 80 drilling machine is not in use for some time since, if the parts rust, they will be left in the safety position. A small port 29 (Fig. 2) may be provided to maintain pressure on the left end of the valve to augment the 85 pressure on spring 27 for holding valve 19 in the safe position. The opposite end of the valve is open at all times to atmosphere by 90 port 30.

Inasmuch as a spacing and holding member 16 for rifle bar 6 is provided to retain the latter in place and to form a piston chamber for piston head 8c of the ratchet ring 8, means must be provided to prevent pawls 7 from interfering with the movement 100 of piston head 8c. This is accomplished by closing the lower ends of the bores in which the pivot ends of pawls 7 are received. By preference the stop means in rifle bar head 6a 105 are integral with the head and effected by 110 terminating the pivot bores somewhat short of the full depth of the head.

From the above it will be apparent that the present invention provides fluid pressure means under convenient control of the operator, as on the control handle, for engaging and disengaging the rotation train, that normally the parts are maintained in the safety position shown in Fig. 1 and automatically 115 return thereto whenever control lever 21 is 120 released by the operator, and that the back head structure involves novel forms of rifle bar, ratchet ring, and holding member for the rifle bar, the latter providing the piston 125 chamber which is utilized in controlling the 130 engaging and disengaging positions of the ratchet ring.

While the invention has been herein disclosed in what is now considered to be a preferred form, it is to be understood that 135

the invention is not limited to the specific details thereof but covers all changes, modifications, and adaptations within the scope of the appended claims.

5 I claim as my invention:

1. A percussive drill having a rotating train for the working tool including a pawl member and a ratchet member, said ratchet member being movable axially and rotatably, 10 and means for locking said member against rotation in one position of axial adjustment.

2. A percussive drill having a rotating train for the working tool including a pawl member and a ratchet member, said ratchet member being movable axially and rotatably, 15 means for locking said member against rotation in one position of axial adjustment, and fluid pressure operated means for axially moving said ratchet member.

20 3. A percussive drill having a rotating train for the working tool including a pawl member and a ratchet member, said ratchet member being movable axially and rotatably, a control handle on said drill, means for locking said ratchet member against rotation in 25 one position of axial adjustment, and means operable from said handle for axially moving said ratchet member.

4. A hammer motor for drilling rock having a rotation train for the working tool including a rifle bar and a ratchet member, the cooperating portions of said bar and member being disposed in a chamber permitting axial movement of the same, means for moving 35 said member longitudinally relative to said bar, means for locking said member against rotation in one position, and means for preventing longitudinal displacement of said rifle bar without interfering with the 40 movement of said member.

5. A fluid pressure percussive machine having rotation mechanism including a ratchet ring and having a chamber in which said ratchet ring is movable, cooperating 45 locking means on said ring and on the walls of said chamber for engagement in one position of said ring to key the latter to said machine, and means for moving said ring into and out of locking engagement with said machine.

50 6. A fluid pressure percussive machine having rotation mechanism including a ratchet ring and having a chamber in which said ratchet ring is movably mounted, cooperating locking means on said ring and on the walls of said chamber for engagement in one position of said ring in said chamber to lock the ring to said machine, and fluid pressure means for moving said ring into and out of 55 said position including a piston head on the latter.

7. A fluid pressure percussive machine having rotation mechanism including a ratchet ring and having a chamber in which said 60 ratchet ring is movable, cooperating locking

means on said ring and on the walls of said chamber for engagement in one position of said ring to lock the latter to said machine, fluid pressure means for moving said ring into and out of locking engagement with said 70 machine, and manual means for controlling said fluid pressure means.

8. A fluid pressure percussive machine having a rotation train including a rifle bar having pawls and a ratchet ring engaged by 75 said pawls, a holding member engaging the pawl end of said bar to retain it in place and providing an annular chamber, said ratchet ring being in telescoping engagement with the pawl end of said bar and having a piston 80 head secured thereto and reciprocable in said chamber, cooperating locking means on said ring and on said machine for engagement in one position of said ring and for disengagement in another position, said ring having 85 ratchet teeth engaged by said pawls in all positions of said ring, and fluid pressure means for moving said ring to and maintaining it in either of said positions.

9. In rotation mechanism for rock drills, 90 a rifle bar having a head having recesses and pivot bores for mounting pawls thereon, said bar having means closing the top of said bores to provide a positive stop for said pawls.

10. In rotation mechanism for rock drills, a ratchet ring having ratchet teeth on its interior, lock teeth on its exterior, and a piston head at one end.

11. In rotation mechanism for rock drills, 100 a ratchet ring having ratchet teeth on its interior, and an annular piston head secured thereto with packing means on its outer and inner peripheries.

12. In rotation mechanism for rock drills, 105 a ratchet ring having ratchet teeth on its interior and an extension providing a piston head.

13. A hammer motor for drilling rock having a rotation train for the working tool including a rifle bar and a ratchet member, the cooperating portions of said bar and member being disposed in a chamber permitting axial movement of the same, means for moving said member longitudinally relative to said 110 bar, means for locking said member against rotation in one position, and means for preventing longitudinal displacement of said rifle bar without interfering with the movement of said member, said last named means serving to guide said moving means.

14. A hammer motor for drilling rock having a rotation train for the working tool including a rifle bar and a ratchet member, the cooperating portions of said bar and member being disposed in a chamber permitting axial movement of the same, fluid pressure means including a piston head on said member for moving the latter longitudinally relative to said bar, means engaged by said member in 115 120 125 130

- one position for locking it against rotation, and means for holding said rifle bar against longitudinal movement and for guiding said piston head.
15. A hammer motor for drilling rock having a rotation train for the working tool including a rifle bar and a ratchet member, the cooperating portions of said bar and member being disposed in a chamber permitting axial movement of the same, fluid pressure means including a piston head on said member for moving the latter longitudinally relative to said bar, said piston head having a bore therethrough, means engaged by said member in one position for locking it against rotation, and a member extending through the bore of said piston head with a sliding fit for holding said rifle bar against longitudinal movement.
16. A fluid pressure percussive machine having rotation mechanism including a ratchet ring and having a chamber in which said ratchet ring is movable, cooperating locking means on said ring and on the walls of said chamber for engagement in one position of said ring to lock the latter to said machine, fluid pressure means including a piston head on said ring for moving the latter into and out of locking engagement with said machine, and manual means for controlling said fluid pressure means.
17. A fluid pressure percussive machine having rotation mechanism including a ratchet ring and having a chamber in which said ratchet ring is movable, cooperating locking means on said ring and on the walls of said chamber for engagement in one position of said ring to lock the latter to said machine, fluid pressure means including a piston head on said ring for moving the latter into and out of locking engagement with said machine, a supporting handle on the machine, and an operating member on said handle for manually controlling said fluid pressure means.
18. A fluid pressure percussive machine having a rotation train including a rifle bar having pawls and a ratchet ring engaged by said pawls, a holding member engaging the pawl end of said bar to retain it in place and providing an annular chamber, said ratchet ring being in telescoping engagement with the pawl end of said bar and having a piston head secured thereto and reciprocable in said member, cooperating locking means on said ring and on said machine for engagement in one position of said ring and for disengagement in another position, said ring having ratchet teeth engaged by said pawls in all positions of said ring, fluid pressure operated means for moving and holding said ring in either position, a holding handle on said machine, and a manually operable member on said handle for controlling said fluid pressure means.
19. A fluid pressure percussive drill having a rotation train including a ratchet ring, locking projections on the exterior of said ring, said drill having cooperating projections for engagement by the projections on said ring releasably to hold the latter against rotation, and means for moving said ring to engage or disengage its projections with the said projections on the drill.
- Signed by me at Detroit, in the county of Wayne and State of Michigan, this 12th day of July, 1930.
